CHARLES F. CONOVER, OF NEW YORK, N. Y.

CONTROL DEVICE FOR STOVES

Application filed October 29, 1929. Serial No. 403,347.

This invention relates to a device adapted to be operated by the overflow of a cooking vessel on a stove, for the purpose of shutting off the heat of the stove in order to avoid accidents.

The principal object of the invention is to provide a device of the indicated character which will be applicable to stoves having one or more burners, so as to be operative for 10 the intended purposes by the overflow of any one of a number of cooking vessels on the stove; and a device which will be simple of construction, and which will be reliable in operation.

15 The nature of the invention and its distinguishing features and advantages will appear when the following specification is read in connection with the accompanying drawings, in which—

20 Figure 1 is a view of a gas stove selected to illustrate the device of the present invention, which is shown applied thereto, portions of the stove being broken away to show certain features of the invention.

25 Fig. 2 is an enlarged section through the flat operated switch of the device.

Fig. 3 is a detail section taken on the line 3—3 of Fig. 1.

The device of the present invention is applicable to cook stoves, whether of the electric type, or of the type which utilizes gas as the heat producing medium. In the present instance, the device is shown, by way of example, applied to a gas stove 10 having a plurality of grids 11, beneath each of which is arranged a suitable heating element or burner 12. The heat producing medium or gas is fed to the burners 12 by a main feed pipe 13 which is in turn connected with the burners 12 respectively by valved branch pipes, constituting the usual construction and arrangement in stoves of this kind.

The device of the present invention includes a pan 14 or other receptacle, which is disposed below the burners 12, and which is sufficiently large to catch any overflow from a cooking vessel supported or resting on any one of the grids 11. The pan 14 inclines downwardly from one side of the stove to the other, and also inclines rearwardly, so

that the overflow liquid from the cooking vessels will be directed toward an outlet 15 formed on or secured to the pan 14. A stop valve 16 is connected in the gas feed pipe 13. The said valve 16 is adapted to be opened to 55 allow the flow of gas to the burners 12, and said valve is also automatically operable to close itself, to stop the flow of the gas. Accordingly, the valve will include a valve member whose stem 17 has secured thereto a rigid 60 member or arm 18. The arm 18 extends laterally from the stem. A spring 19 surrounds the stem 17 and has one end thereof secured to the body of the valve, and the opposite end thereof is in engagement with the arm 18. 65 The spring 19 has a normal tendency to move the valve member of the valve to a closed position, to stop the flow of gas. Holding and releasing means is provided to hold the valve open, and which is operable to allow 70 the valve to close itself. The said means is in the form of an electromagnet 20, positioned on the stove adjacent the valve 16. The electromagnet 20 includes a pivotally mounted spring pressed armature 21, which 75 is engageable with the arm 18 to hold it in a position in which the spring 19 will be under tension, with the valve member connected therewith in the opened position. The electromagnet 20 is electrically connected in electric circuit 22 including a source of electrical energy 23, and a pair of spaced contact members 24. The contact members 24 are positioned on and insulated from a casing 25. 80 The said casing 25 will be attached in any suitable manner to the stove for instance. A metal float 26 of spherical form is arranged in the casing 25, and is adapted to bridge the contact members 24 when a certain amount of 85 liquid finds its way into the casing 25. The casing 25 has an inlet 27 at the bottom thereof with which an L-shaped pipe 28 is connected. The upper end of the pipe 28 has a funnel 29 in registry with the outlet 15 of 90 the pan 14. The inlet 27 has connected therewith a drain cock 30 for the purpose of draining liquid from the casing 25.

From the foregoing it will be apparent that the overflow liquid from any cooking vessel

arranged on the stove will be caught by the pan 14. This overflow liquid will find its way to the outlet 15 of the pan into the casing 25, through the pipe 28 and the inlet 27. 5 This liquid on reaching the casing 25 will cause the float 26 to rise and bridge the contact members 24, closing the circuit 22. The closing of the circuit 22 will cause the energization of the pole pieces of the electromagnet 20, which latter, will attract the armature 21, and therefore move the same out of engagement with the arm 18. The spring 19 will then come into play and move the valve member of the valve into the closed position, 10 thereby stopping the flow of gas to the particular burner or burners. It will therefore be appreciated that when a cooking vessel boils over due to overheating, it is apt to put out the flames of the burner, while the gas continues to flow and fills the room, which is very dangerous, and liable to cause an explosion, or asphyxiate a person or persons. The device of the present invention serves adequately to avert these serious accidents, 15 as will be apparent from the foregoing description. It will also be understood that the device serves adequately to prevent vessels from burning out due to overheating which will cause the overflow of liquid necessary to operate the device. 20

It is also to be understood that the device may be applied to an electrical stove to prevent burning out of cooking vessels and unnecessary waste of current. The device when 25 applied to an electrical stove will include a self-closing switch in lieu of the valve 16, and such switch will control the supply of current to the heating elements or burners of such stove.

40 I claim:

In combination, a cook stove having a heating element, a pan beneath said heating element to catch overflow liquid from a vessel arranged on the stove and being heated by the 45 heat of said element, said pan having an outlet, means which supplies a heat producing medium to said heating element, a device adapted to be opened to allow the flow of said medium, and also operable to automatically 50 close to stop the flow of said medium, an electric circuit, an electromagnet in said circuit whose armature is adapted to hold said device open and operable to attract the armature to allow said device to automatically 55 close, spaced contact members in said circuit, a casing on which said contact members are arranged, a metal float in said casing adapted to bridge said contact members to close the 60 circuit to energize the electromagnet whereby the electromagnet will attract its armature to allow said device to close automatically, said casing having an inlet in registry with said outlet to allow liquid leaving 65 the outlet to flow into said casing to raise said

float to cause the latter to bridge said contact members.

Signed at Brooklyn, in the county of Kings and State of New York, this 24th day of October, 1929.

CHARLES F. CONOVER.
